Primary Examiner — Lilyana Bekic(74) *Attorney, Agent, or Firm* — Dorsey & Whitney LLP(57) **CLAIM**

We claim the ornamental design for an oral irrigator tip, as shown and described.

DESCRIPTION

This application is related to U.S. Nonprovisional Application Ser. No. 15/923,744 filed Mar. 16, 2018 and entitled “oral irrigator handle for use with oral agent”, which is hereby incorporated by reference in its entirety for all purposes.

FIG. 1 is an isometric view of an oral irrigator tip, showing our new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The dash-dash broken lines illustrate portions of the oral irrigator tip that form no part of the claimed design. The dash-dot broken lines define the boundaries of the claimed design and form no part thereof.
